[57] CLAIM

The ornamental design for the anti-snoring sleep wear, as shown.

DESCRIPTION

FIG. 1 is a front elevational view of the anti-snoring sleep wear showing my new design;

FIG. 2 is a rear elevational view thereof;

FIG. 3 is a front elevational view of a second embodiment thereof;

FIG. 4 is a rear elevational view thereof;

FIG. 5 is a bottom plan view of both embodiments thereof, and,

FIG. 6 is a bottom plan view of both embodiments thereof. The broken lines on the bottoms of the pockets on FIG. 1 and 4 represent conventional stitching.
